US00D736921S

(12) **United States Design Patent**
Richard et al.

(10) **Patent No.:** **US D736,921 S**
(45) **Date of Patent:** ** *Aug. 18, 2015

(54) **SEAL ANCHOR FOR USE IN SURGICAL PROCEDURES**

(71) Applicant: **Covidien LP**, Mansfield, MA (US)

(72) Inventors: **Paul D. Richard**, Shelton, CT (US);
Russell Heinrich, Madison, CT (US)

(73) Assignee: **Covidien LP**, Mansfield, MA (US)

(*) Notice: This patent is subject to a terminal disclaimer.

(**) Term: **14 Years**

(21) Appl. No.: **29/493,028**

(22) Filed: **Jun. 5, 2014**

Primary Examiner — Wan Laymon

CLAIM

The ornamental design for the seal anchor for use in surgical procedures, as shown and described.

DESCRIPTION

FIG. 1 is a top perspective view thereof;

FIG. 2 is a top plan view thereof;

FIG. 3 is a side elevational view thereof; and,

FIG. 4 is a bottom plan view thereof.

The broken lines shown in the figures represent portions of the seal anchor for use in surgical procedures that form no part of the claimed design.

1 Claim, 2 Drawing Sheets
